CLAIM

The ornamental design for a bra, as shown and described.

DESCRIPTION

FIG. 1 is a front perspective view of a bra in a first configuration;

FIG. 2 is a rear perspective view of the bra of FIG. 1;

FIG. 3 is a front elevation view of the bra of FIG. 1;

FIG. 4 is a rear elevation view of the bra of FIG. 1;

FIG. 5 is a left side view of the bra of FIG. 1;

FIG. 6 is a right side view of the bra of FIG. 1;

FIG. 7 is a top plan view of the bra of FIG. 1;

FIG. 8 is a bottom plan view of the bra of FIG. 1;

FIG. 9 is a front perspective view of the bra of FIG. 1 in a second configuration;

FIG. 10 is a rear perspective view of the bra of FIG. 9;

FIG. 11 is a front elevation view of the bra of FIG. 9;

FIG. 12 is a rear elevation view of the bra of FIG. 9;

FIG. 13 is a left side view of the bra of FIG. 9;

FIG. 14 is a right side view of the bra of FIG. 9;

FIG. 15 is a top plan view of the bra of FIG. 9; and,

FIG. 16 is a bottom plan view of the bra of FIG. 9.

The evenly broken lines (dash-dash lines) shown in FIGS. 1, 2, 9, and 10 depict environment and form no part of the claimed invention.

1 Claim, 14 Drawing Sheets
